UNITED STATES PATENT OFFICE.

EDGAR F. HATHAWAY, OF BOSTON, MASSACHUSETTS, ASSIGNOR TO AMERICAN WARP DRAWING MACHINE COMPANY, OF BOSTON, MASSACHUSETTS, A CORPORATION OF MAINE.

HEDDLE.

1,246,002.

Specification of Letters Patent.

Patented Nov. 6, 1917.

Application filed October 5, 1912, Serial No. 724,049. Renewed March 22, 1917. Serial No. 156,740.

To all whom it may concern:

Be it known that I, EDGAR F. HATHAWAY, a citizen of the United States, residing in Boston, in the county of Suffolk and State 5 of Massachusetts, have invented an Improvement in Heddles, of which the following description, in connection with the accompanying drawings, is a specification, like characters on the drawings representing like 10 parts.

This invention relates to heddles, and more particularly to heddles having means for facilitating the separation of the heddles by automatic mechanical separation, or 15 by hand separation, preparatory to drawing the warp threads through the thread-receiving eyes of the heddles.

My invention will be best understood by reference to the following specification, 20 when taken in connection with the accompanying illustration of one specific embodiment thereof, while its scope will be more particularly pointed out in the appended claims.

25 In the drawings:

Figure 1 is an elevation of several heddles embodying my invention, supported in a heddle frame; and

Fig. 2 is an enlarged sectional view on 30 line 2--2 of Fig. 1, illustrating the location of the heddle separating means, with respect to the direction of the warp threads.

Referring to the drawings, and to the embodiment of my invention therein disclosed for illustrative purposes, I have there shown for the purposes of exemplification supporting means for the heddles comprising a heddle frame 5 having braces, or girts, 35 6--6, in which upper and lower heddle holding bars 7 and 8 are supported and held in place by latches 9--9 and 10--10.

The heddles may be supported in any desired manner upon the heddle frame, but herein are perforated at both ends in a well-known manner to receive the holding bars 40 by which they are supported. While the heddles may be of any desired style or type, I have shown for purposes of exemplification heddles of the flat metallic type. The 45 heddles may be provided with any suitable

spacing means for facilitating the separation of the heddles, but herein each heddle is provided with one or more lateral projections, preferably located at the upper portion of the heddle.

In the present instance, I have chosen to employ two sets of heddles, a set of heddles 11 and a set of heddles 12, the one set alternating with the heddles of the other set, the heddles of one set differing in configuration 55 from the heddles of the other set as to the separating or spacing means. While this difference in configuration may be of other character, in the present instance, the difference is in the placing of the spacing means 60 on the heddles. Herein the heddles 11 are provided with lateral projections 13, and the heddles 12 are similarly provided with projections 14, but the two sets of projections are located out of alinement with each other, or in other words, they are located at different points longitudinally of the heddles.

Preferably the heddles 11 are provided with a second set of projections 15, and the heddles 12 are similarly provided with projections 16, these sets of projections being 65 also located out of alinement with each other, or in other words, being disposed at different points longitudinally of the heddles.

The projections of the two sets of heddles may be 70 described as being placed in staggered relation by having the spacing means of each heddle differently located from the spacing means of the next adjacent heddle or heddles.

By utilizing two sets of spacing 75 means as described, there is insured between the two sets of spacing means a certain definite spacing of the heddles in a direction at right angles thereto, which spacing will exist regardless of the degree of compactness 80 of the heddles. In other words, between the upper and lower sets of spacing means, there is a certain portion of the heddles which is definitely and accurately spaced, regardless 85 of the spacing of the eyes or other portions of the heddles. This accurate spacing of the heddles is very advantageous when it is desired to separate the heddles by means of automatic mechanical separating devices, 90 preparatory to the drawing of warp threads 95 100.

through the thread-receiving eyes 17 and 18 of the heddles.

By reference to Fig. 2, it will be observed that warp threads 19 pass through the 5 thread-receiving eyes of the heddles in the customary manner at right angles to the plane of the heddles. The heddle spacing means are herein disposed at an angle to the warp threads, so as to give the heddles the 10 described definite spacing in the plane of the heddles, or at right angles to the warp threads.

While I have herein shown and described 15 one specific embodiment of my invention for illustrative purposes, and have disclosed and discussed in detail the construction and arrangement incidental to one specific application thereof, it is to be understood that the invention is limited neither to the mere 20 details or relative arrangement of parts nor to its specific embodiment herein shown, but that extensive deviations from the illustrated form or embodiment of the invention may be made without departing from the 25 principles thereof.

Having thus described my invention, what I claim and desire by Letters Patent to procure is:—

1. In a harness, the combination of a pair 30 of holding bars of a series of detached, independent heddles connected at their opposite ends to said bars and having each a thread perforation intermediate its ends, spacing means for holding the heddles separated at a point appreciably away from the bars, said means comprising a plurality of separated corrugations transversely arranged on each heddle and facing the next adjacent heddle, the corrugations on one 40 heddle being offset with reference to those on the next adjacent heddle.

2. In a harness, the combination of a pair 45 of holding bars of a series of detached, independent metallic heddles connected at their opposite ends to the bars, said heddles having each a thread perforation intermediate its ends and spacing means for holding the heddles separated comprising a plurality of separated lateral projections on each heddle, 50 said projections being located appreciably away from the bars and separated by an amount to insure a separation space between the heddles of substantial length.

3. In a harness, the combination of a pair 55 of holding bars of a series of detached, independent, metallic heddles connected to the bars at their opposite ends and having each a thread perforation intermediate its ends, said heddles having each a spacing formation located appreciably away from the bars and adapted to insure a separation between adjacent heddles for a substantial portion of their length at a point between the bars.

4. In a harness, the combination of a pair

of supporting bars of a series of detached, independent, metallic heddles connected at their opposite ends to said bars, said heddles having each a thread perforation intermediate its ends and spacing means for holding said heddles separated, said means comprising a plurality of lateral projections in each heddle located appreciably away from the bars but in such proximity to each other as to insure a substantial space separation 75 between adjacent heddles at a point intermediate the bars, said projections being offset on adjacent heddles. 70

5. In a harness the combination with supporting means of a series of detached, independent heddles having each a thread perforation intermediate its ends and spacing means for holding the heddles separated at a point appreciably away from the supporting 80 means, said spacing means comprising a plurality of spaced, lateral projections, the heddles being arranged in two sets having their spacing projections arranged in alternation. 85

6. In a harness the combination with supporting means of a series of detached, independent, metallic heddles having each a thread perforation intermediate its ends and having each a spacing formation at a point appreciably away from the supporting 90 means and adapted to insure at that point and for a short distance lengthwise the heddle an appreciable space between successive heddles. 95

7. In a harness the combination of supporting means of detached, independent, metallic heddles having each a thread perforation intermediate its ends, and a plurality of separated spacing projections adapted to contact with the next adjacent heddle 100 and to provide thereat and at a point appreciably away from the supporting means a separation between each heddle and the adjacent heddle for a substantial portion of its length. 105

8. As a new article of manufacture, a flat, metallic heddle having a thread receiving perforation, a support engaging formation and a rectilinear portion appreciably separated from the support engaging formation 110 provided with a plurality of lateral separated spacing projections. 115

9. As a new article of manufacture a flat, metallic heddle having a thread-receiving formation, a support-engaging formation 120 and a rectilinear portion having a plurality of transverse, separated, spacing corrugations located upon the same flat face of the heddle and appreciably removed distant from the support-engaging formation. 125

10. A series of detached, independent heddles having each a threading eye intermediate its ends and having each a plurality of lateral spacing projections adapted to engage with the next adjacent heddle and 130

insure a space between the same, said projections being also intermediate the ends of the heddle but separated by a distance relatively small as compared with the total length of the heddle.

5 In testimony whereof, I have signed my

name to this specification, in the presence of two subscribing witnesses.

EDGAR F. HATHAWAY.
